Official Action Dated Nov. 19, 2014 From the US Patent and Trademark Office Re. U.S. Appl. No. 29/438,226.

Primary Examiner — David Muller*Assistant Examiner* — Nathan Johnston(74) *Attorney, Agent, or Firm* — Kristina Bieker-Brady; Clark & Elbing LLP(57) **CLAIM**

The ornamental design for a capsuled colostomy bag, as shown and described.

DESCRIPTION

FIG. 1 is a left side view of a capsuled colostomy bag showing our new design;

FIG. 2 is a bottom view thereof;

FIG. 3 is a rear view thereof;

FIG. 4 is a right side view thereof;

FIG. 5 is a front view thereof;

FIG. 6 is a top view thereof;

FIG. 7 is a perspective view thereof; and,

FIG. 8 is a perspective view thereof showing the colostomy bag in a deployed position.

The broken lines represent portions of the capsuled colostomy bag that form no part of the claimed design.
